US0D1114389S

(12) **United States Design Patent** (10) **Patent No.:** **US D1,114,389 S**
(45) **Date of Patent:** **** Feb. 17, 2026**

(54) **PET SHAVING BRUSH**

(71) Applicant: **Hong Jiang**, Hunan (CN)

(72) Inventor: **Hong Jiang**, Hunan (CN)

(**) Term: **15 Years**

(21) Appl. No.: **29/978,824**

(22) Filed: **Dec. 16, 2024**

(51) LOC (15) Cl. **30-99**

(52) U.S. Cl.

USPC **D30/159**; D32/42; D32/46

(58) **Field of Classification Search**

(57) **CLAIM**

The ornamental design for a pet shaving brush as shown and described.

DESCRIPTION

FIG. 1 is a perspective view of a pet shaving brush showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.
